UNITED STATES PATENT OFFICE

170,672

FOLDING TABLE

Albert M. Zalkind, Arlington, Va.

Application February 25, 1953, Serial No. 23,774

Term of patent 14 years

(Cl. D33—14)

To all whom it may concern:

Be it known that I, Albert M. Zalkind, a citizen of the United States, residing at Arlington, State of Virginia, have invented a new, original, and ornamental Design for a Folding Table, of which the following is a specification, reference being had to the accompanying drawing, forming a part hereof.

Fig. 1 is a side perspective view of a folding table, showing my new design.

Fig. 2 is a front perspective view thereof.

Fig. 3 is a rear elevational view thereof in folded position.

Fig. 4 is a side elevational view thereof in folded position.

I claim:

The ornamental design for a folding table, as shown.

ALBERT M. ZALKIND.
